LOOM TEMPLE ROLL

William McCaskie, New Bedford, Mass.

Application December 15, 1941, Serial No. 423,019

5 Claims. (Cl. 139—296)

This invention relates to loom temple rolls, and more particularly to improved roll structures having novel gripping surfaces for engaging the selvage edges of the cloth to move the same outwardly during the beating up action of the lay.

One object of the invention is the provision of temple rolls having fabric covered cloth engaging surfaces which are provided with or comprise spirally arranged raised portions forming ribs serving to engage and move the selvage edges of the cloth outwardly as the rolls are rotated by the forward movement of the cloth.

Another object of the invention is the provision in devices of this character of a fabric covering for temple rolls formed from or having incorporated therein a tractive or resilient material adapted to engage resiliently or grip the cloth as it presses into engagement therewith without forming roll marks in the selvage edges of the cloth.

A further object of the invention is the provision of devices of this character formed with cores of substantially rigid material which are provided with spirally ribbed surfaces having tubular fabric sections sleeved thereon which form, with the ribbed surfaces of the core, face projecting spiral ribs for engaging the cloth.

Another object of the invention is the provision in devices of this character of cloth engaging fabric surfaces which have been treated to render the fabric resistant to the action of acids, oils or alkalies which may be present in the fibres of the cloth being woven.

Other objects and advantages of the invention relate to various improved details of construction and novel arrangements of the parts as will be more fully set forth in the detailed description to follow.

Referring to the drawing:

Fig. 1 is a top plan view of a portion of a loom temple, showing the same in operative relation with cloth in the process of its formation on a loom,

Fig. 2 is a side elevational view, partially in section, as taken along the line 2—2 of Fig. 1, showing one operative position of the loom temple rolls in connection with a holder head of conventional type,

Fig. 3 is a side elevational view, partially in section, of one form of roll structure embodying the invention,

Fig. 4 is a similar view of a somewhat modified form of roll structure, and,

Fig. 5 is a similar view of a further modified form of temple roll.

Heretofore, various forms and types of roll structures have been provided for use in loom temples to engage the selvage edges of the cloth being woven for holding the edges outwardly and preventing abrasion of or injury to the warp threads by the reed as the lay beam moves to beat up the threads. Devices of this character, as previously employed, range from pin studded rolls to rolls having spirally ribbed toothed surfaces formed from a variety of materials. In the use of rolls of the character described it is found that those having sharp cloth engaging face portions tend to break the threads and form holes in the selvage edges of the cloth, while it is common for certain of such rolls to indent the cloth leaving more or less permanent marks in the selvage edges, all of which detracts from the appearance and value of the cloth.

The present invention is adapted to overcome these defects by providing a roll structure having a fabric cloth engaging outer surface which will not injure or indent the formed cloth, even when using the finest threads and forming the most fragile material.

In the form of the invention illustrated herein, 1 designates generally a loom temple, which may be secured to the breast beam of a loom in the usual or any suitable manner, and which comprises a head 2 having a pod portion 3 and cap 4 for receiving loom temple rolls 5 which may be rotatably supported by shafts 6 suitably mounted in the end walls of the pod 3 or cap 4 of the loom temple head. The cap 4 may be mounted for adjustment towards or from the pod 3 and secured in the desired adjusted relation relative thereto by screws or bolts 7. As shown in Fig. 1 of the drawing, the cloth being formed is indicated by the reference character 8 and is engaged by the temple rolls slightly in advance of the fell 9.

The temple roll 5 shown in Fig. 3 of the drawing comprises a core 10 formed with a shaft receiving opening 11 extending therethrough, which core may be formed from wood or any other suitable natural or synthetic material adapted for the purpose and may have a rigid or slightly resilient outer surface as may be found desirable in practice. In the form of the invention shown in Fig. 3 of the drawing, the core 10 is provided with an enlarged rounded central portion 12, upon which are formed one or more raised spiral ribs 14, and the core has reduced end portions 15.

A tubular formed fabric section 16 of suitable material is sleeved over the enlarged central portion 12 of the core and has ends 17 extending

outwardly therefrom and adapted to be engaged and held by metal caps 18 mounted on the reduced ends 17 of the core portion of the roll. The inner ends 19 of the metal caps 18 may be spun down over the adjacent ends 17 of the fabric 16 to hold the fabric cover firmly in position upon the enlarged central portion 12 of the core. The opposite end 20 of each cap 18 is turned to fit over the free end of its reduced end portion 15, as shown at the right in Fig. 3 10 of the drawing. The raised spiral rib or ribs 14 formed on the central portion 12 of the core press the tubular fabric section 16 outwardly to form a raised spiral rib or ribs 22 therein for engagement with the cloth to hold the central 15 portion thereof taut as the rolls are rotated by engagement with the cloth being formed. The tubular fabric section 16 may be woven, as on a circular loom, braided, or otherwise formed by cylindrically interlacing the strand material 20 both longitudinally and circumferentially of the tubular shape, and may be made of any desired fibrous or non-fibrous material suitable for the purpose. The invention comprehends the forming of the tubular sections from ordinary textile material, and treating the same, when desired, with a suitable surface coating, such as a rubber composition, latex or lacquer, or in impregnating the fibres of the tubular fabric with a suitable lacquer or proofing material, such as 25 Bakelite, to render the fabric impervious to the action of acids or alkalis which may be present in the cloth being formed. I may also incorporate threads or strands of tractive material, such as rubber, asbestos, Buna-S, Koroseal, or Neoprene in the woven or braided tubular sections to give them added traction upon the cloth.

In the form of the invention shown in Fig. 4 of the drawing, the roll 24 comprises a core 25 having a shaft receiving opening 26 formed therein and shaped to provide an enlarged central cylindrical portion 27 and reduced ends 28. The enlarged central portion 27 may have a cylindrical outer surface 29 to receive a tubular fabric section 30, which may be woven, braided or otherwise formed, and which, as shown, has incorporated therein a spirally positioned cord or enlarged strand 32 woven, braided or otherwise embodied within the tubular fabric section. Metal caps 33 are fitted over the reduced ends 28, and the inner end of each cap is spun inwardly or otherwise pressed into position to engage firmly one of the free ends of the tubular fabric section 30 to hold the same firmly in position upon the enlarged central portion 27 of the core.

In the form of the invention shown in Fig. 5 of the drawing, the roll 35 has a core member 36 provided with a shaft receiving opening 37, and is of a shape similar to that shown in Fig. 4 of the drawing, having a central enlarged cylindrical portion 38, having a cylindrical outer face 39, and reduced end portions 40. In this form of the invention a tubular fabric cover 42 may, as in the preceding forms, be woven, braided or otherwise formed, and is shown as provided with a plurality of slightly raised thread portions 44 which are spaced from each other and so positioned in the tubular fabric as to form together one or more substantially continuously extending, spirally arranged, raised, cloth engaging areas in 70 the tubular fabric which project outwardly slightly beyond the remaining surface of the tubular fabric to engage the selvage edges of the cloth being formed and move the same outwardly as the rolls are rotated through movement of the 75

cloth. In this, as in the forms previously shown, metal caps 46 may be employed having ends forced into engagement with or spun over the free ends 47 of the tubular fabric cover 42 to hold the fabric cover securely in position upon the enlarged central portion 38 of the core.

In each form of the invention, the tubular fabric cover may be made from any suitable or desired form of woven, braided or knitted fibrous material, such as, silk, rayon, cotton, ramie, or the like, and may have incorporated therein filaments or threads of rubber, asbestos, or other material adapted to exert a tractive force on the surface of the cloth being formed. The tubular fabric may be and is preferably treated, especially when formed from a single fibrous material, such as cotton, wool, rayon or the like, by being partially or wholly impregnated with a suitable lacquer, or the like, such as Bakelite, to render the fibres more or less impervious to the action of acids, oils or alkalis, which may be present in the cloth being formed and in order to preserve the fabric material against distortion. In each case, the tubular fabric material may be firmly secured to the enlarged central portion of the core member by being glued or otherwise secured thereto throughout all or a portion of its extent so that it will maintain an even surface throughout, or it may be secured thereto only at the outer ends, as by means of the metal end caps.

In the forms shown in Figs. 4 and 5, the spirally positioned heavy cord or thread 29 and the enlarged or raised thread portions 44 may be formed from or contain threads of rubber, Neoprene, Buna-S, Koroseal, asbestos fibres or the like, or from any other suitable form of thread or cord adapted to exert a high tractive effect upon the cloth being formed.

In each form of the invention shown the rolls may be positioned in the holder to engage either the top or bottom surface of the cloth being formed, or they may be arranged to engage opposite side faces of the cloth, as has been the practice heretofore with various forms of temple rolls.

What I claim is:

1. A loom temple roll comprising a substantially cylindrical core member, and a tubular cover formed from strands cylindrically interlaced together throughout the longitudinal and circumferential extent of the tubular shape sleeved upon the core member and having a raised spiral rib portion formed therein and projecting outwardly radially of the tubular cover beyond the remaining surface portions thereof when the tubular cover member is in position upon said core member.

2. A loom temple roll comprising a substantially cylindrical core member provided upon its outer face with a raised spiral rib, and a tubular cover member formed from strands cylindrically interlaced both longitudinally and circumferentially of said tubular cover, said cover member being sleeved upon said core member and secured thereto, whereby portions of the tubular cover member project outwardly radially beyond the remaining surface portions of the cover member to form a cloth engaging raised spiral rib.

3. A loom temple roll comprising a core member having a substantially cylindrical face portion, and a lacquer impregnated tubular fabric cover formed from interlaced fibrous strands, sleeved upon the cylindrical portion of said core

member and secured thereto, said cover when sleeved upon the core member having portions thereof projecting outwardly radially of the core member to form a substantially continuous raised spiral rib portion for engagement with the cloth being formed in advance of the remaining outer face portions of the cover.

4. A loom temple roll comprising a core member having a substantially cylindrical outer face portion, and a longitudinally integrated tubular cover member formed throughout from cylindrically interlaced fibrous strands sleeved upon the cylindrical outer face portion of said core member and secured thereto, said tubular cover member having an enlarged strand element incorporated within the fibrous strands forming the body thereof and extending spirally of the tubular sec-

tion to provide a raised spiral rib portion upon the outer face thereof when the tubular fabric cover section is mounted upon the cylindrical portion of the core member.

5. A loom temple roll comprising a substantially cylindrical central core member, a woven tubular fabric cover comprising strand elements incorporated within the woven fabric material and having portions thereof arranged to project outwardly radially of the cover to form a raised spiral rib portion for engaging the surface of the cloth being formed in advance of the remaining surface areas of the cover member, when said cover member is sleeved upon and secured to said cylindrical core member.
